UNITED STATES PATENT OFFICE

CLIFFORD LAKIN-SMITH, OF WESTMINSTER, LONDON, ENGLAND

PLUNGER PUMP

Application filed January 3, 1930, Serial No. 418,273, and in Great Britain January 3, 1929.

This invention relates to pumps of the type in which the axis of a pair of oppositely disposed pistons or plungers is arranged transversely to the axis of rotation of the pump, the effective reciprocation of the pistons or plungers being obtained by a crank, or an eccentric pin arranged in a guide arranged at right angles to the piston or plungers. The object of the invention is to increase the efficiency of such pumps without increasing their size, and without providing additional cylindrical pistons or plungers.

The present invention consists of a piston or plunger pump of the kind in which the plunger or piston rod has a transverse guide or slot in which operates a crank or eccentric pin, wherein the liquid displacement of the pump is increased by the crank or eccentric pin or a block carried thereon operating in the transverse guide or slot of the piston rod or plunger to draw—during the operation of the piston or plunger pump—liquid into the guide or slot and then displace it through one or more ports provided in addition to those provided for the main piston or plunger.

The invention further comprises a plunger pump having rigidly connected oppositely disposed plungers between which is provided a transverse guide having a slot in which operates a crank or eccentric enclosed in a casing provided with inlet and outlet fluid passages, wherein the crank pin or eccentric during its relative movement in the slot of the transverse guide draws fluid into the slot through a port at one end of the guide and during a further stage of the operation displaces the fluid through the same port and through the outlet of the casing.

The invention is equally applicable to a pump of the kind in which a rotary carrier containing radial cylinders rotates around a pin arranged eccentrically to effect the reciprocation of the piston or plungers relatively to the cylinders, as to a pump in which the radial cylinders are fixed and the pistons or plungers are reciprocated by a rotating crank.

A manner of carrying out the invention is illustrated by the accompanying drawings

wherein Figure 1 is a transverse sectional elevation and Figure 2 a longitudinal sectional elevation of the complete pump, Figure 3 is an elevation of the plungers, Figure 4 an elevation of the rotor, and Figure 5 a transverse section of the plungers through A—A of Figures 1 and 3.

In these drawings $c1$ and $c2$ are two oppositely disposed cylinders bored diametrically in a rotor formed of two portions $2a$ and $2b$ by a plane at right angles to its axis, the two portions being detachably connected together by bolts passed through holes $2s$. In the cylinders $c1$ and $c2$ reciprocate an integral pair of coaxial plungers $5a$, $5b$, the mid portion of the plungers being shaped to form a transverse guide $5g$ having a slot in which reciprocates a block 6 rotatively mounted on a fixed or adjustable eccentric pin 3 . The ends $5e$ and $5f$ of the transverse guide $5g$ are arranged to slide on oppositely disposed parallel surfaces $2c$ and $2d$ provided in the rotor $2a$, $2b$, parallel to the axis of the cylinders $c1$, $c2$. The surfaces $2c$, $2d$ are provided with intermediate ports or openings $2e$, $2f$ respectively, arranged between the cylinders $c1$ and $c2$ which extend to the periphery of the rotor $2a$, $2b$ so that they will rotate over inlet and outlet passages $4a$ and $4b$ provided in the casing 4 of the pump. The periphery of the rotor is arranged to move over concave portions of the casing on shoes $4c$ and $4d$ provided in the casing 4 between the inlet and outlet passages $4a$ and $4b$.

The dimensions of the outer ends of the ports $2e$ and $2f$ at the periphery of the rotor $2a$, $2b$ are preferably made to agree with those of the open ends of the cylinders $c1$ and $c2$, so that the timing relation of all the displacement elements will be the same.

The ends $5e$ and $5f$ of the transverse guide $5g$ connecting the plungers $5a$ and $5b$ are each provided with a port $5d$ registering with the corresponding adjacent port $2e$ or $2f$ of the rotor $2a$, $2b$ and with walls $5c$ from which the pistons $5a$ and $5b$ extend.

The rotor $2a$, $2b$ is arranged in the usual manner in the cylindrical casing 4 which is provided with the inlet $4g$ leading to the passage $4a$ and an outlet $4h$ leading from the

passage 4b. The casing 4 is provided with one removable end 4e in which is supported the eccentric pin 3 by a nut 3a, and which has an inwardly extending boss 4i forming a bearing for a boss 2i extending from the portion 2a of the rotor. The opposite side or end of the casing has a bearing face against which rotates the other portion 2b of the rotor, the portion 2b of the rotor is also provided with a shaft 2j which is the driving shaft of the pump and which passes through a gland 4k.

In pumps of this type it is necessary to provide some clearance between the projecting portions of the transverse guide 5g and the inner cavities 2m, 2n, of the rotor, as in the present construction liquid may leak into such cavities or clearance spaces, and in order to balance the pressure between the cavities 2m and 2n they are connected by passages formed by grooves or recesses 5m formed in the transverse guide 5g.

The device may be duplicated on the same shaft, the pistons of one section being arranged at right angles to those of the next section. When such duplication is effected communication between the sections may be prevented by means of discs arranged between the guide members of each unit. These discs may be so arranged that their outer peripheries bear on the inner surfaces of the carrier ring while they have a hole arranged eccentrically in them to fit over the eccentric pin. In such modifications the inlets and outlets may be coupled in any desired manner such as for instance to give a parallel effect or a series or compound effect.

The invention is also applicable to each pair of oppositely disposed cylinders of pumps having more than one pair of integral or double ended plungers rotating in the same plane.

What I claim and desire to secure by Letters Patent is:—

1. A pump comprising in combination two coaxial and oppositely disposed cylindrical plungers, a transverse rectangular guide-way arranged between and connecting the two oppositely disposed plungers and forming liquid displacement chambers transversely to the plungers, a rotor having diametrically opposed cylinders in which the plungers are reciprocated by the rectangular guide-way, parallel flat surfaces provided in the rotor parallel to the axis of the plungers and on which slide the outer ends of the guide-way and supporting the plungers independently of the cylinders, the outer ends of the guide-way being constructed as shoulders on the plungers and the inside of the rotor and grooves formed in the shoulders placing the opposite cavities in communication with each other, the rotor being also provided with intermediate ports diametrically arranged at right angles to the cylinders and passing

through flat parallel surfaces, a pump casing bored to receive the rotor and having a liquid inlet and a liquid outlet separated by shoes projecting into the casing and forming a portion of the bored surface of the casing in which the rotor rotates, means whereby the rotor can be rotated, a fixed pin secured eccentrically in the casing and extending into the guide-way, a block rotatable on said pin and adapted to slide in the guide-way, ports being provided in the opposite ends of the guide-way and opening into the intermediate ports provided in the rotor so that during the rotation of the rotor, liquid will be drawn into one end of the guide-way while the port communicating therewith passes the inlet of the pump and will be driven through the same end of the guide-way while the port communicating therewith passes the outlet of the pump.

2. A rotary pump comprising in combination two coaxial and oppositely disposed cylindrical plungers, a transverse rectangular guide-way arranged between and connecting the two oppositely disposed plungers and forming liquid displacement chambers transversely to the plungers, a rotor having diametrically opposed cylinders in which the plungers are reciprocated by the rectangular guide-way, parallel flat surfaces provided in the rotor parallel to the axis of the plungers and on which slide the outer ends of the guide-way and supporting the plungers independently of the cylinders, the outer ends of the guide-way being constructed as shoulders on the plungers and the inside of the rotor and grooves formed in the shoulders placing the opposite cavities in communication with each other, the rotor being also provided with intermediate ports diametrically arranged at right angles to the cylinders and passing through the flat parallel surfaces, a pump casing having a chamber to receive the rotor and having a liquid inlet and a liquid outlet separated by oppositely disposed walls which project into the casing and form a portion of the surface of the said chamber in which the rotor rotates, means whereby the rotor can be rotated, the rotor being divided at right angles to its axis into two detachably connected side portions, a fixed pin secured eccentrically in the casing and extending into the guide-way, a rectangular block rotatable on said pin and adapted to reciprocate in the guide-way, ports being provided in the opposite ends of the guide-way and opening into the intermediate ports provided in the rotor so that during the rotation of the rotor, liquid will be drawn by the rectangular reciprocating block into one end of the guideway while the port communicating therewith passes the inlet of the pump and will be driven through the same end of the guide-way while the port

communicating therewith passes the outlet of the pump.

3. A pump comprising in combination two coaxial and oppositely disposed cylindrical plungers, a transverse rectangular guide-way arranged between and connecting the two oppositely disposed plungers and forming liquid displacement chambers transversely to the plungers, a two-piece rotor having diametrically opposed cylinders in which the plungers are reciprocated by the rectangular guide-way, parallel flat surfaces provided in the rotor parallel to the axis of the plungers and on which slide the outer ends of the guide-way and supporting the plungers independently of the cylinders, the outer ends of the guide-way being constructed as shoulders on the plungers and the inside of the rotor and grooves formed in the shoulders placing the opposite cavities in communication with each other, the rotor being formed of two pieces secured together and divided transversely to its axis and the axes of the cylinders, the said rotor being also provided with

intermediate ports diametrically arranged at right angles to the cylinders and passing through the flat parallel surfaces, a pump casing shaped to receive the rotor and having a liquid inlet and a liquid outlet separated by 70 shoes projecting into the casing and forming a portion of the surface of the casing in which the rotor rotates, means whereby the rotor can be rotated, a fixed pin secured eccentrically in the casing and extending into the 75 guide-way, a block rotatable on said pin and adapted to slide in the guide-way, ports being provided in the opposite ends of the guide-way and opening into the intermediate ports 80 provided in the rotor so that during the rotation of the rotor, liquid will be drawn into one end of the guide-way while the port communicating therewith passes the inlet of the pump and will be driven through the same end of the guide-way while the port communicating therewith passes the outlet of the 85 pump.
